UNITED STATES PATENT OFFICE.

JOHN F. DAVIS, OF FREEPORT, MAINE.

SHOE-SOLE.

1,258,878.

Specification of Letters Patent. Patented Mar. 12, 1918.

Application filed November 2, 1916. Serial No. 129,049.

To all whom it may concern:

Be it known that I, JOHN FREDERICK DAVIS, a citizen of the United States, residing at Freeport, county of Cumberland, 5 State of Maine, have invented certain new and useful Improvements in Shoe-Soles, of which the following is a specification.

This invention relates to shoe structures, and particularly to a shoe in which flexibility and softness are required. In my previous Patent, No. 989,950, granted to me on the eighteenth day of April 1911, I disclosed a shoe of the type to which my present invention relates, but my present invention 15 involves certain improvements applicable to this type of shoe in general, and particularly to the form of shoe shown therein.

In that form of shoe some manufacturing difficulties have been experienced in lasting 20 at the ball portion where the interposed cushion part is embodied. In order to improve and strengthen the shoe at this point as well as to facilitate its manufacture, I have provided for the combination of the 25 elements of the insole with a special fastening member which provides for the combination of these elements into a unit piece as well as providing for a member which may be employed as a fastening member to hold the parts and to facilitate the lasting.

In the accompanying drawings I have shown a form which I have found well adapted in practical manufacture and use, and which well serves as an illustrated embodiment to which reference may be made 35 in the accompanying specification.

In the drawings:

Figure 1 is a plan view of the inner side of my new sole member.

40 Fig. 2 is a plan view of the opposite side. Fig. 3 a longitudinal section.

Fig. 4 a view of an upper lasted with my new sole member, and

45 Fig. 5 is a sectional detail of the fastening element.

I construct my sole portion of a heel and shank piece 2 which may be of reinforced canvas or any other suitable material, and a toe piece 3 which may be of any suitable 50 material, preferably leather. The intermediate filling placed below the ball portion of the foot is preferably of felt as indicated at 4. These three elements are assembled preferably by fastening to a thin slip 5 and are then fastened together by a pair of mem-

bers 6, one on each side of the sole at the opposite margins of the ball portion.

These fastening members 6 are preferably of canvas, although they may be of any desired material. These strips are of sufficient 60 length to traverse the central portion 4 and overlap the toe portion 3 and the heel and shank portion 2 being stitched through as indicated at 7 so as to unite these parts. The portion 6, as shown in Fig. 2, is of sufficient 65 width so that after the parts have been united by the stitching 7, it may be folded as indicated in Fig. 5, to form a fastening member to which the upper 9 may be sewn by a series of stitches 8.

70 In practising my invention, the sole member is first produced as stated above by assembling the toe part 3, the ball part 4 and the heel and shank part 2 upon a backing 5, and sewing on the member 6 to unite 75 them. This sole member is then placed upon the last and the margins of the upper 9 drawn over it and secured by tacking where necessary. The edges of the upper adjacent to the ball portion are then fastened by a 80 line of stitching 8. This stitching operation not only unites the edges of the upper with the fastening member of the sole, but has a lasting effect in that the upper is drawn in at the same time that it is sewn. The shoe 85 is then fastened in the usual manner. I am thus able to produce a shoe which has great flexibility and ease and yet which is very strong and durable.

90 Various modifications may obviously be made in the above structure within the spirit of my invention, and within the limit of the appended claims.

What I therefore claim and desire to secure by Letters Patent is:

95 1. In a shoe structure of the type described, a sole member comprising a heel and shank part, a toe part and an intermediate cushion member, a marginal fastening strip on each side of the sole and attaching said three members in position, and an upper fastened along the ball of the sole to said fastening member.

100 2. In a shoe structure of the type described, a sole member comprising a thin inner sole, a heel and shank part, a toe part and an intermediate cushion member assembled thereon, a fastening member overlapping the members of the sole and united by suitable fastenings to each of said mem- 110

- bers, and an upper fastened along the ball of the sole to said fastening member.
3. A sole member comprising a heel and shank part, a toe part and an intermediate cushion member, and a marginal fastening strip on each side of the sole attaching said three members in position, and constructed and arranged to provide an upper attaching area.
- 10 4. A sole member comprising a plurality of adjacent independent transverse sections and a lapped fastening strip on each side of the sole and secured to each of said sections, said strips having an upper attaching area.
- 15 5. A sole, comprising a shank part, a toe part, and an intermediate tread part, and a marginal fastening strip secured to each of said parts and attaching said parts in position and constructed and arranged to provide an upper attaching area.
- 20
6. A sole, comprising a plurality of independent sections, and a flexible marginal fastening member overlapping said sections and secured to each and attaching said sections in position, and having an upper attaching area.
7. A sole, comprising a plurality of adjacent sections, and a foldable fastening strip overlapping said sections and secured to each and attaching said sections in position, said strip of sufficient width to provide when folded longitudinally an upper attaching area.
- In testimony whereof I affix my signature in presence of two witnesses.
- JOHN F. DAVIS.
